UNITED STATES PATENT OFFICE

128,323

DESIGN FOR A DRESS

Perkins H. Bailey, New York, N. Y.

Application October 17, 1940, Serial No. 95,904

Term of patent 3½ years

To all whom it may concern:

Be it known that I, Perkins H. Bailey, a citizen of the United States, residing at New York, in the county of New York and State of New York, have invented a new, original, and ornamental Design for a Dress, of which the following is a specification, reference being had to the accompanying drawing, forming part thereof.

In the drawing:

Fig. 1 is a front view of a dress according to this design;

Fig. 2 is a rear view of the dress shown in Fig. 1; and

Fig. 3 is a view, similar to Fig. 1, of the dress in open position.

I claim:

The ornamental design for a dress, substantially as shown.

PERKINS H. BAILEY.
